UNITED STATES PATENT OFFICE

132,459

DESIGN FOR AN ORTHOPTIC INSTRUMENT OR ARTICLE OF SIMILAR NATURE

Le Roy Wottring, Altadena, Calif., assignor to
The Wottring Instrument Company, Amherst,
Ohio, a corporation of Ohio

Application February 19, 1942, Serial No. 105,917

Term of patent 14 years

To all whom it may concern:

Be it known that I, Le Roy Wottring, a citizen of the United States of America and a resident of Altadena, in the county of Los Angeles and State of California, have invented a new, original, and ornamental Design for an Orthoptic Instrument or Article of Similar Nature, of which the following is the specification, reference being had to the accompanying drawing, forming a part thereof.

Figure 1 is a front perspective view of an

orthoptic instrument or article of similar nature showing my new design.

Figure 2 is a rear perspective view of the instrument shown in Figure 1.

Figure 3 is a top perspective view showing my new design.

I claim:

The ornamental design for an orthoptic instrument or article of similar nature, substantially as shown.

LE ROY WOTTRING.
